UNITED STATES PATENT OFFICE.

GEORGE RAMSEY, OF BROOKLYN, NEW YORK, ASSIGNOR TO ANCHOR CAP AND CLOSURE CORPORATION, OF LONG ISLAND CITY, NEW YORK, A CORPORATION OF NEW YORK.

INTERRUPTED BEAD CAP.

Application filed January 27, 1921. Serial No. 440,299.

To all whom it may concern:

Be it known that I, GEORGE RAMSEY, a citizen of the United States, residing in the borough of Brooklyn, in the county of 5 Kings, State of New York, have invented certain new and useful Improvements in Interrupted Bead Caps, of which the following is a specification.

This invention relates broadly to packaging and more specially to a friction cap and the package sealed by the friction cap.

The principal object of the present invention is the provision of a friction cap having a sealing zone made up of a plurality of 15 spaced apart contact portions angularly disposed over the depth of the skirt of cap.

Another object of the present invention is a friction cap provided with a plurality 20 of spaced apart sealing members adapted to comprise a wave-like sealing zone in the skirt of the cap.

A still further object of the present invention is a friction cap having a plurality of 25 spaced apart sealing zones adjacent both the upper and lower edge of the skirt of the cap.

A still further object of the present invention is a friction cap having a sealing zone thereof comprising a plurality of spaced apart sealing contact members adapted to 30 provide yielding zones in the skirt of the cap forming friction sealing members to co-operate with a smooth cylindrical side walled vessel to provide a friction sealed package.

Another and further object of the present invention is a friction cap of the character 35 specified comprising a suitable skirted cap with angularly disposed individual sealing members arranged in the skirt of the cap and with a suitable gasket carried by a cap 40 in such manner that when the cap is forced over the mouth of a substantially incompressible container a friction seal is formed between the cap and the container, and the gasket forms a hermetically sealed package 45 by contacting with the end of the side wall of the container.

Other and further objects of the present invention will in part be obvious and will 50 in part be pointed out hereinafter in the specification following by reference to the accompanying drawings and wherein like parts are represented by like characters throughout the several figures thereof.

It is realized that the present invention

may be embodied in forms other than those 55 herein shown and described therefore it is desired that the disclosures herein shall be considered as illustrative and not be taken in the limiting sense.

Figure 1 illustrates one embodiment of the 60 present invention and comprises a cap ready to be sealed upon a suitable container.

Figure 2 illustrates another embodiment of the invention in slightly different form with a portion of the cap skirt broken away 65 to show a gasket.

Figure 3 illustrates a further modification of the invention.

Figure 4 shows a still further form of the 70 present invention and

Figure 5, illustrates a still further form of sealing bead.

Heretofore in the art of friction caps there have generally been three types of 75 caps. First the cylindrical skirted type usually applied to metal cans and limited to close fitting sized containers because of the small limit of elasticity in the skirt. The second type comprises the straight continuously beaded cap with the bead concave on 80 the exterior and the skirt convex on the interior. Such caps require accurate application otherwise the bead may be deformed and the seal spoiled. The third type, are caps having separated spots or sections of 85 beads arranged on substantially the same plane, or diameter so that the maximum sealing effort is required at one time and where- 90 in the stress of the skirt of the cap is transmitted to one zone in the skirt. This type has the same objections as the full bead type.

There is a fourth type of cap which is disclosed in my prior application No. 400,396 95 filed July 31, 1920, comprising a sinuous bead cap and the present invention is a modification of the broad invention disclosed in the said sinuous bead application. The disclosure of the broad invention comprises continuous sinuous beads of various forms and in that type the flexibility of 100 the skirt during the sealing action is dependent largely on the stretching of the bead. In the present invention the bead comprises separate spots, which when taken together form the sealing zone, and with a slight expanse of the cap skirt between each of these spots so that when the cap expands 105 in sealing these portions tend to increase the

flexibility of the skirt thereby increasing the sealing range of the cap so that greater variations both as to size and distortion of glass containers may be sealed. This is of 5 great importance to the packer since in the manufacture of glass containers the container is usually removed from the mold before the glass is thoroughly hardened and it is not unusual for the carrying or lifting 10 operation to slightly distort the shape of the glass so in the trade it is known as "out of round." Furthermore molds are not all of uniform diameter and even if they were the glass may change slightly in diameter 15 during the annealing or other manufacturing steps. It is the purpose of friction seal caps of various types to accommodate the cap to imperfect glassware within as large a range of limits as possible in order to permit 20 the user to utilize the general run of glassware rather than to greatly increase expense by requiring a special selection of substantially perfect ware as to size and shape. Furthermore it is important that 25 the sealing action take place with a minimum use of power in order to save breakage and waste of energy. The present invention is designed more specially with these objects in view and it provides a very flexible skirt having sealing members thereof arranged to provide a tight gripping seal and at the same time is constructed in such manner that the sealing forces are spread 30 out over the time required to force the whole skirt over the mouth of the container rather than to require the maximum sealing forces at one moment. This permits of lighter machinery, of less liability of glass breakage and makes the driving load on the packer's 35 factory more uniform.

Referring now to the drawings and more specially to Figure 1 which illustrates one embodiment of the invention comprising a cap A having a cover portion 1 with a skirt 2 depending from said cover portion, and preferably with the beaded edge 4 which may comprise a wired edge or simply a slight outward roll in order to finish the rough edge of the skirt. The skirt may be 45 provided with spaced apart indentations which may take the form of spots or buttons 5 and 6 which are convex on the interior of the skirt and concave on the exterior thereof with the buttons designated as 50 5 comprising a series arranged adjacent the lower edge of the skirt and the buttons designated as 6 comprising a series forming a row adjacent the upper edge of the skirt and with the buttons of the two rows arranged 55 in staggered relation. The lower row of buttons 5 extends inwardly sufficient so that the maximum diameter measured 60 from the inner tips of the buttons is less than the maximum diameter of the cylindrical portion 7 of the container B. This

container preferably is of glass or the like having substantially incompressible side walls. As the cap is forced downwardly over the mouth of the container B the inner points of the buttons 5 will contact with 70 the upper rounded edge of the container and will gradually stretch or flatten as the telescoping movement of the cap continues. Where the package is being formed in open air the confined air in the container escapes 75 between the skirt of the cap and the side wall of the container in the spaces provided between the buttons 5 so that the danger of producing compressed gas in the container during sealing is obviated and where the cap is set under a vacuum these spaces facilitate the withdrawal of the air from the package. As the cap further telescopes on the container the upper row of spots or buttons 6 is forced over the mouth of the container and form additional holding members. It will be noted that the staggered relation of the members in the upper and lower rows tends to permit a slight stretching 80 of the skirt on diagonal lines thereby producing a condition of resilience which enables the user to utilize the cap on relatively large variations in sizes of containers. Where no gasket is used the cap is admirably adapted for caps which are used to 85 package materials which require contact with the air, in that it permits the circulation of air between the side wall of the cap and container body.

Where a hermetic seal is desired the gasket C may be arranged to lie in the upper edge or corner of the cap. This gasket may be of soft compressible material as is commonly used in the art or may comprise a flat rubber gasket, which is also in common use. 90 Where a flat gasket is used preferably the upper portion of the skirt of the cap is provided with a groove 8, such as is indicated in Figure 2, and the outer edge of the gasket may lie in this groove thereby being held 95 in position during the handling or applying of the cap.

Figure 2 illustrates the friction gripping members as being V-shaped members 9 so that during the sealing operation these members first engage the upper edge of the container by the lower tips of the V-shaped members and as the cap and the container are telescoped the sealing zone gradually extends diagonally from the lower points, 115 but in view of the fact that the upper ends of the V's are spaced apart an open space is left up until the final moment of sealing against the gasket and may be retained even after the cap is in position by omitting the 120 gasket C.

In the cap shown in Figure 3 the sealing members comprise spaced apart diagonal groups 10 and 11 which are convexed on the interior of the skirt and concave on the 130

- exterior thereof, and likewise air passages are maintained during sealing and the diagonal stressing effect of the skirt on the cap is also accomplished. In Figure 4 the gripping members 12 are illustrated as being substantially semi-circular grooves arranged in spaced apart series so that the diagonal stresses on the skirt are maintained at the same time the open passageways are presented. In the form illustrated in Figure 5 the gripping members 13 are shown as being inverted V-shaped members which produce an effect similar to the form shown in Figure 2.
- 15 The drawings illustrate but a few of the many variations of which the present invention is capable and which all embody the same general principles; comprising stressing the skirt diagonally and providing the free passages beneath the skirt of the cap to the interior of the container up until the final sealing moment, where a gasket is used, thereby particularly adapting the present cap to be used where a hermetic seal is obtained at the final sealing moment and wherein the passageways beneath the cap facilitate exhausting the air in the package up until the instant of completing the seal.
- Having thus described my invention, what I claim is:
1. As an article of manufacture a closure cap comprising a cover portion, a skirt depending from the cover portion, and a plurality of spaced apart holding projections formed on the interior of said skirt, the arrangement of the projections being such that when the cap is applied the skirt thereof is stressed on diagonal lines and wherein air passages are provided between the said projections and the side wall of a suitable container during the sealing operation.
  2. As an article of manufacture a closure cap comprising a cover portion, a skirt depending from the cover portion, and a plurality of spaced apart holding projections formed on the interior of said skirt, the arrangement of the projections being such that when the cap is applied the skirt thereof is stressed on diagonal lines.
  3. As an article of manufacture a closure cap comprising a cover portion, a skirt depending from the cover portion, and a plurality of spaced apart holding projections formed on the interior of said skirt, said projections being adapted to be flattened in the sealing operation and the arrangement of the projections being such that when the cap is applied the skirt thereof is stressed on diagonal lines and wherein air passages are provided between the said projections and the side wall of a suitable container during the sealing operation.
  4. As an article of manufacture a closure cap comprising a cover portion, a skirt depending from the cover portion, and a plurality of spaced apart holding projections arranged on the interior of said skirt, the arrangement of the projections being such that when the cap is applied the skirt thereof is stressed on diagonal lines, a portion of the projections being in the lower part of the skirt and another portion being in the upper part of the skirt, and wherein air passages are provided between the said projections and the side wall of a suitable container during the sealing operation.
5. As an article of manufacture a closure cap comprising a cover portion, a skirt depending from the cover portion, and a plurality of spaced apart holding projections formed on the interior of said skirt, said projections being adapted to be flattened in the sealing operation, and the arrangement of the projections being such that when the cap is applied the skirt thereof is stressed on diagonal lines, a portion of the projections being in the lower part of the skirt and another portion being in the upper part of the skirt.
6. A closure cap comprising a cover portion, a skirt extending at substantially right angles to said cover portion, a plurality of spaced apart holding members arranged to project inwardly from the side wall of said skirt and adapted to contact with the side wall of a suitable container, said members being arranged to subject substantially the entire skirt to diagonal stresses when the cap is applied and with the sealing forces increasing from the initial application of the cap until substantially the final setting thereof on a suitable container.
7. A closure cap comprising a cover portion, a cylindrical skirt extending at substantially right angles to said cover portion, a plurality of spaced apart holding members arranged to project inwardly from the normal side wall of said cylindrical skirt and adapted to contact with a smooth side wall of a suitable container, said members being arranged to subject substantially the entire skirt to diagonal stresses when the cap is applied.
8. A closure cap comprising a cover portion, a skirt on said cover portion, a plurality of spaced apart holding members arranged to project inwardly from the side wall of said skirt and adapted to contact with the side wall of a suitable container, said members being diagonally arranged to subject substantially the entire skirt to stresses when the cap is applied and with the sealing forces tending to hold the cap in place increasing from the initial application of the cap until substantially the final setting thereof on a suitable container.
9. A friction closure cap comprising a cover portion, a skirt extending from the cover portion, and a sealing bead in said skirt portion comprising a plurality of

spaced apart members arranged to produce sinuous stresses in said skirt when the cap is applied to a suitable container.

10. A friction closure cap comprising a cover portion, a skirt extending from the cover portion, and a sealing bead in said skirt portion comprising a plurality of inwardly projecting spaced apart members arranged to produce sinuous stresses in said 10 skirt when the cap is applied to a suitable container, said members being adapted to contact with said container at spaced apart intervals.

11. A friction closure cap comprising a cover portion, a skirt extending from the cover portion, and a sealing bead in said skirt portion comprising a plurality of spaced apart diagonally arranged friction members adapted to produce sinuous stresses 20 in said skirt when the cap is applied to a suitable container.

12. A closure cap comprising a cover portion, a skirt extending from said cover portion, a sealing bead provided in said skirt and comprising a plurality of spaced apart sealing members arranged to provide passageways between the exterior and interior of said container, and with the members arranged to increase the friction contact 25

surface between the cap and a suitable container as the cap is telescoped over the container.

13. As an article of manufacture a package comprising a container having a substantially incompressible side wall, in combination with a closure cap comprising a cover portion, a skirt depending from the cover portion and telescoped over the mouth of said containers, and a plurality of spaced apart holding projections formed on the 40 interior of said skirt, the arrangement of the projections being such that the said skirt is stressed on diagonal lines and wherein air passages are provided between the said projections and the side wall of the container.

14. As an article of manufacture a package comprising a container having a substantially incompressible side wall, in combination with a closure cap comprising a 50 cover portion, a skirt depending from the cover portion, and a plurality of spaced apart holding projections formed on the interior of said skirt, the arrangement of the projections being such that the said skirt is 55 stressed on diagonal lines when in position on said container.

GEORGE RAMSEY.
